ABSTRACT OF THE DISCLOSURE

A stable reagent having avidity for the agglutination reaction in the serological determination of rheumatoid factors is composed of rabbit gamma globulin which is degraded with a proteolytic enzyme, coated on latex particles, heat treated and stored at low temperatures until used. This reagent is capable of identifying true positives when the sodium chloride of the serum diluent is maintained within certain critical limits.

The present application is a continuation-in-part of our copending application, Ser. No. 558,255, filed June 17, 1966 now abandoned.

The present invention relates to a method for the serological determination of agglutinating factors, commonly called rheumatoid factors, that are found in the sera of patients suffering from rheumatoid arthritis. More particularly, the invention relates to a stable reagent for the quantitation of the rheumatoid factors and to the method for its preparation, and particularly the conditions under which it is used.

The sera of many patients with rheumatoid arthritis contain high molecular weight gamma globulins possessing a sedimentation constant of 19 S. These protein moieties have been termed rheumatoid factors and the detection of rheumatoid factors in sera is a convenient means for the early diagnosis of rheumatoid arthritis.

Nonbiological particles such as polystyrene latex, acrylic resins and bentonite that have been sensitized with human gamma globulin have been used to detect rheumatoid factor. U.S. Pat. 3,088,875 teaches one such diagnostic reagent. Although these tests are used widely, they can best be classified as general screening tests in that they are extremely sensitive, but at the same time yield a considerable number of false positive results as has been described by Heiner and Rudd, *Arth. & Rheumat.*, 5:110 (1962).

Attempts to quantitate the level of rheumatoid factor in the serum of patients by tube test procedures employing these sensitized particles frequently result in astronomically high titers that bear less relation to the clinical condition of the patient than to the particular preparation of human gamma globulin used for sensitization.

Biological particles are also used as carriers for the apparent antigens of the rheumatoid factor. When human red blood cells are used, either selected human gamma globulin containing specific nonagglutinating anti-D (Rh_0) is used for the sensitization, or the red blood cells are first treated with a reagent such as tannic acid which alters the surface properties so that protein is readily but nonspecifically adsorbed. Neither of these two procedures has received the widespread acceptance accorded to the sheep red blood cell-rabbit anti-sheep cell test first described by Waaler [Acta Path. Microbiol. Scand., 17:172 (1940)], and subsequently by Rose et al. [Proc. Soc. Exper. Biol. & Med., 68:1 (1948)].

Although the reasons for the specificity of the sheep cell

2

test are not known, its specificity has been amply demonstrated by clinical follow up of patients whose sera has revealed positive test reactions. Tube test titers seldom extend beyond 1:5000 and stand in contrast to titers obtained with either tanned and sensitized red blood cells or sensitized latex which may extend beyond 1:100,000.

Despite the reliability of the Waaler-Rose sheep cell test, its use has been somewhat curtailed due to the instability of the red blood cell carrier. Standardization and 10 sensitization of red blood cells are time consuming procedures that must be performed at frequent intervals.

It is the primary object of the present invention to provide a stable nonbiological particle sensitized with rabbit gamma globulin to obtain a sensitive, specific reagent for rheumatoid factor.

15 It is another object of the invention to provide a tube test confirming reagent to be used whenever positive reactions are obtained with a rapid screening type of test procedure.

20 It is still another object of the invention to provide a test reagent which mimics the titers obtained with the sheep red cell test.

25 It is a further object to provide test conditions that will render the confirming agent capable of identifying true positives.

30 In the test of the present invention, the reagents consist of latex sensitized with rabbit gamma globulin and a buffer system. The test is made by preparing doubling dilutions in a series of test tubes of the blood serum using

35 the buffer with a critical concentration of sodium chloride as diluent and adding an equal volume of latex reagent. The tubes containing the serum-latex mixture are then placed at 56° C. for 2 hours and at +4° C. overnight. If rheumatoid factors are present in the test serum, a direct reaction is evidenced by agglutination of the particles of the latex reagent. If there is no rheumatoid factor present, the latex reagent will remain smoothly suspended throughout the fluid medium. Reaction can be graded with respect to the degree of agglutination present.

40 Polystyrene particles having an average diameter of from 0.15 micron to 14 microns, but preferably 0.81 micron are used to prepare the latex system. Acrylic particles having an average within the same range may also be used.

45 The test will not function properly with ordinary rabbit gamma globulin. Treatment of the rabbit gamma globulin to alter its antigenic properties is essential to the test. The alteration found most effective is accomplished by enzyme treatment of the rabbit gamma globulin prior to sensitization of the latex particles. The latex reagent is then heat treated to complete the alteration of the rabbit gamma globulin. Heat treatment at 50° C. for a period of 7 to 10 days has been found to be effective.

50 Higher temperatures for shorter periods of time are also effective. For example, heat treatment of the latex reagent at 100° C. (boiling) for 2 to 5 minutes was found to be effective. In the alternative heating at 70° C. for approximately 5 days can be practiced. However, heating of the latex reagent in the absence of prior enzyme treatment does not result in a suitable reagent.

55 Several enzymes have been tested and found satisfactory for alteration of the rabbit gamma globulin, namely crude and crystalline trypsin, chymotrypsin and papain. Fungal proteases and pepsin have been found only partially effective. While the nature of the alteration of the rabbit gamma globulin is not fully understood, presumably the reactivity of rheumatoid factor with rabbit globulin depends upon sites that are unavailable after adsorption of the rabbit globulin onto latex. Fragmentation of the globulin molecules by various proteolytic enzymes provides a means by which vital portions of the

structure become available. In the case of trypsin or chymotrypsin treated rabbit gamma globulin, the whole product of fragmentation may be used for the preparation of the test reagent. When papain is employed as the enzyme, isolation of the relatively insoluble portion of the fragmented rabbit gamma globulin and selection of the more nearly soluble part of this fraction is desirable. In any event the yields of treated rabbit globulin on latex particles is relatively low compared to the trypsin or chymotrypsin treated material. Heating of the fragmented material can be expected to result in further collapse of the native structure which exposes the desired reactive site areas.

In contrast, human gamma globulin treated in the manner described becomes grossly nonspecific and unfit for reagent purposes. Pretreatment of human gamma globulin prior to sensitization of the latex has not been found to enhance the reactivity while still maintaining the specificity of the reaction.

A further difference in the reagents consisting of human and rabbit gamma globulin can be seen in the buffer systems required. Whereas sodium chloride in a borate buffer system enhances the speed of reaction of human globulin sensitized latex, a concentration beyond 0.1 M sodium chloride in borate buffer negates the reaction of the rabbit gamma globulin. A concentration above 0.05 M sodium chloride in borate buffer results in a substantial increase in the number of false positives. A salt concentration of 0.025 M in borate buffer yields optimum reactions. Concentrations of sodium chloride below 0.025 M result in insolubility of serum proteins, and consequent precipitation of these proteins.

The effective critical concentration of sodium chloride is the concentration of that salt in the serum diluent. Normal human serum has a concentration of 0.15 M sodium chloride. However, the first dilution in a tube test involves 0.1 ml. of serum with 1.9 ml. of 0.025 M borate buffer containing 0.025 M sodium chloride. This 1:20 dilution results in an effective sodium chloride concentration close to 0.025 M. Further dilutions (1:40, 1:80, 1:160, etc.) bring the concentration even closer to 0.025 M sodium chloride.

The following examples illustrate the preparation of the reagent.

EXAMPLE I

100 milligrams of rabbit gamma globulin are dissolved in 5 milliliters of 0.1 M borate buffer, pH 8.6. Crude trypsin equal to one-tenth the weight of rabbit gamma globulin is added to the globulin-buffer solution and brought to a temperature of 37° C. and maintained at that temperature for one hour. The enzyme digested gamma globulin is then diluted to 50 ml. with 0.1 M borate buffer, pH 8.6 and is added slowly with constant stirring to 50 milliliters of a two percent by weight suspension of polystyrene particles in which the particles have an average diameter of 0.81 micron. Thimerosal is added in a final concentration of 1:5000. The resulting material is brought slowly to a temperature of 50° C. and maintained at that temperature for 10 days. Salt free bovine serum albumin is added to a final concentration of 0.1% for stabilizing purposes and the material thus prepared is stored at +4° C.

EXAMPLE II

100 milligrams of rabbit gamma globulin are dissolved in 5 milliliters of 0.1 M borate buffer, pH 8.6. Crude trypsin equal to one-tenth the weight of rabbit gamma globulin is added to the globulin-buffer solution and brought to a temperature of 37° C. and maintained at that temperature for one hour. The enzyme digested gamma globulin is then diluted to 50 ml. with 0.1 M borate buffer, pH 8.6 and is added slowly with constant stirring to 50 milliliters of a two percent by weight sus-

pension of polystyrene particles in which the particles have an average diameter of 0.81 micron. Thimerosal is added in a final concentration of 1:5000. The resulting material is brought to a temperature of 93° C., and maintained at that temperature for 10 minutes. The material thus prepared is stored at +4° C.

EXAMPLE III

100 milligrams of rabbit globulin is dissolved in 5 milliliters of 0.05 M phosphate buffer pH 7.1. Papain equal to one-fiftieth of the weight of rabbit gamma globulin is added to the globulin-buffer solution and brought to a temperature of 37° C. and maintained at that temperature for one hour. The preparation is then dialysed against borate buffer pH 8.6, diluted to fifty milliliters with the same buffer and added slowly with constant stirring to 50 milliliters of a two percent by weight suspension of polystyrene particles in which the particles have an average diameter of 0.81 micron. Thimerosal is added in a final concentration of 1:5000. The resulting material is brought slowly to a temperature of 50° C., and maintained at that temperature for 10 days. The material thus prepared is stored at +4° C.

The reagent of this invention may be employed as the initial test for rheumatoid arthritis or as the confirming test. The faster, but less accurate slide test based on human gamma globulin may be used for the initial screening test when large numbers of tests are involved. The following example will serve to illustrate the employment of the reagent in testing for rheumatoid arthritis.

EXAMPLE IV

In conducting the confirming test for rheumatoid factor utilizing the reagent of the invention, blood serum from a patient which has given a positive response in screening test for rheumatoid factor is used. The reagent as prepared in any one of Examples I to III is diluted 1:20 with 0.025 M borate buffer. Ten 12 x 75 mm. glass test tubes are placed in a rack. Doubling dilutions of the serum are prepared as follows:

0.1 ml. of the patient's serum is pipetted into tube #1. 1.9 ml. of 0.025 M borate buffer containing 0.025 M sodium chloride is added to tube #1 and 1.0 ml. of the same buffer is added to the remaining nine tubes. The contents of tube #1 are mixed and 1.0 ml. of the contents of tube #1 are transferred to tube #2. The contents of tube #2 are mixed and 1.0 ml. thereof is transferred to tube #3. The transfer from one tube to the next progresses through tube #9 and 1.0 ml. of the final contents of tube #9 is discarded. Tube #10 is the control.

1.0 ml. of the diluted reagent is then added to each of the ten tubes. The contents of the tubes are mixed well and incubated for 2 hours at 56° C. The tubes are then maintained at 4° C. overnight. The reactions are read for agglutination of particles and clarity of supernate. The results are recorded as negative (an even suspension comparable to the control), ±, 1+, 2+, 3+, or 4+.

The tubes may be centrifuged and thereafter shaken gently before observing the agglutination. However, centrifuging requires substantial skill for determination of the approximate centrifugal force and time. Hence, the preferred practice is to maintain the tubes overnight at 4° C. instead of centrifuging.

The following tables show the results of confirmation tests where a positive response was obtained in a latex slide screening test. The highest doubling dilution at which agglutination occurred with the reagent of the invention is compared with the highest doubling dilution of the Waaler-Rose sheep cell test. In each of these tables, the reliable Waaler-Rose test data indicated true positive responses and the latex slide test data and the latex tube test data (i.e., the reagent of this invention) also showed positive responses. The latex slide test employed is substantially that disclosed in U.S. Pat. 3,088,875.

TABLE 1.—PATIENTS UNDER CLINICAL OBSERVATION WITH AN ESTABLISHED DIAGNOSIS OF RHEUMATOID ARTHRITIS

Not only is it necessary to enzyme treat the rabbit gamma globulin prior to adsorption to latex and to employ a heating step on the latex reagent itself, but it is also critical to control the salt concentration of the final

reaction mixture consisting of diluted patient serum (1 ml., using a buffer solution containing sodium chloride within the critical range described hereinbefore) and latex reagent (0.1 ml.). The following tables illustrate the criticality of the sodium chloride concentration during the test.

TABLE 4.—TUBE TEST USING LATEX REAGENT OF EXAMPLE I

10	Composition of the serum diluent buffer	Dilutions of a patient's serum known to contain rheumatoid factors in low titer			
		1:20	1:40	1:80	1:160
15	0.05 M borate plus no NaCl	*3	1	0	0
	0.025 M borate plus 0.001 NaCl	3	1	0	0
	0.025 M borate plus 0.005 NaCl	3	1	0	0
	0.025 M borate plus 0.01 NaCl	3	1	0	0
	0.025 M borate plus 0.025 NaCl	3	2	1	0
	0.025 M borate plus 0.05 NaCl	3	2	—	0
	0.025 M borate plus 0.10 NaCl	3	1	0	0
	0.025 M borate plus 0.15 NaCl	1	0	0	0
20	0.025 M borate plus 0.20 NaCl	0	0	0	0

*The results are recorded as negative (an even suspension comparable to the control), ±, +, 2+, 3+, or 4+.

TABLE 5.—TUBE TEST USING LATEX REAGENT OF EXAMPLE I

30	Composition of the serum diluent buffer	Dilutions of a patient's serum known to contain rheumatoid factors in high titer					
		1:20	1:40	1:80	1:160	1:320	1:640
30	0.025 M borate plus 0.025 M NaCl	3	4	4	3	2	2 +
	0.025 M borate plus 0.05 M NaCl	1	1	2	2	2	2 +

35 It can be seen that salt affects the two serum titration reactions differently. However, unless the optimum concentration is used, the reaction is affected adversely. Optimum sensitivity is requisite for the test as is avoidance 40 of prozoning of high titered sera.

What is claimed is:

1. A reagent for determining rheumatoid factor in human serum comprising latex particles, having an average diameter of from about 0.15 micron to about 14 microns, coated with a proteolytic enzyme-treated rabbit gamma globulin, said globulin having been prepared by adding to rabbit gamma globulin in a buffered solution, pH 7.1-8.6, a proteolytic enzyme selected from the group consisting of trypsin, chymotrypsin and papain and heating at 37° C. for one hour, said coated latex particles having been treated for 5-10 days at temperatures from 50-70° C. or for 2-5 minutes at temperatures from 93-100° C.
2. The reagent of claim 1, wherein said latex particles are polystyrene particles having an average diameter of 0.81 micron.
3. The reagent of claim 1, wherein said enzyme is added to said rabbit gamma globulin dissolved in 0.1 M borate buffer having a pH of 8.6.
4. The method of determining the presence of rheumatoid factor in human serum which comprises preparing doubling dilutions of human serum with a buffer solution containing sodium chloride in the range of 0.025 M to 0.05 M, adding to said dilutions a buffered suspension of 60 the reagent of claim 1, incubating said serum-suspension mixtures at about 56° C., reducing said temperature to about 4° C., and observing said mixtures for agglutination.
5. The method of claim 4 wherein said serum-suspension mixtures are observed for agglutination after maintaining them at 4° C. overnight.
6. The method of claim 4 wherein said serum-suspension mixtures are observed for agglutination after centrifugation.
